UNITED STATES PATENT OFFICE.

WALDEMAR PETERSEN, OF DARMSTADT, GERMANY, AND WILHELM HESS, OF BASEL, SWITZERLAND, ASSIGNORS TO THE SOCIETY EMIL HAEFELY & CO. A. G., OF BASEL, SWITZERLAND.

TRANSFORMER FOR HIGH VOLTAGE.

Application filed April 20, 1921. Serial No. 462,931.

To all whom it may concern:

Be it known that we, WALDEMAR PETERSEN, a citizen of the Republic of Germany, and resident of Darmstadt, Germany, and 5 WILHELM Hess, a citizen of the Swiss Republic, and resident of Basel, Switzerland, have invented new and useful Improvements in Transformers for High Voltages, of which the following is a full, clear, and exact specification.

It has hitherto been customary to construct transformers for voltages above approximately 30,000 volts with oil insulation, on the ground that the high insulating properties of a good special oil permit the design of the insulation to be reduced to a minimum. On the other hand oil insulation causes difficulties, inasmuch as the incipient discharges from the solid insulating material, which in time cause perforation, can only be obviated with great difficulty and at considerable cost. A further objection with oil transformers is the impossibility of detecting such discharges in time to obviate them. In the case of testing transformers for very high voltages in particular, on account of the usually brief period of operation, the heating of the upper layers of oil is too slight to ensure a natural circulation of oil; as a result when at any point in the transformer an incipient discharge has been formed, this tends to increase in intensity owing to the want of a fresh supply of oil, and finally causes break down or perforation 30 of the insulation.

According to the present invention an air transformer is employed in which the incipient discharges which are harmful in oil are utilized for obtaining a graduated electric field distribution as the ionized insulating material (air) is continually renewed, whilst the solid insulating material with a suitably proportioned field density is not attacked by what may be called streamer discharges. This condition is attained in an air transformer having coaxial high and low tension windings according to the invention, by the fact that an insulating hollow body surrounding the low tension winding, 45 and a second insulating hollow body surrounded by the high tension winding, are separated from one another by a large, entirely free air space which is so proportioned that in the high tension field brush discharges or sparks cannot occur but only

streamer discharges, which permit of a linearly decreasing drop of potential between the high tension winding and the iron core.

The invention is illustrated in the accompanying drawings of which—

Figure 1 is a view in side elevation partly sectional and

Figure 2 a plan view partly sectional of a transformer constructed in accordance with one form of the invention.

Figures 3, 4, 5, 6, 7, 8, 9, 10, 11 and 12 show by partial vertical sections different forms of a discharge ring or shield for protecting the high tension winding.

Referring now to Figures 1 and 2 the low tension winding *a* is usually placed over the arms of the iron core *b*. A hollow insulating cylinder *c* composed of material having a high dielectric coefficient surrounds the winding *a* and provides for a uniform distribution of the lines of force of the electric field in the air space hereinafter referred to. By providing an earthed metal lining *d* for the hollow insulating cylinder *c* this equalizing effect is increased. The air space *f* extends around the hollow insulating cylinder *c* and is enclosed externally by the outer hollow insulating cylinder *g*, the air space thus enclosed between said cylinders *c* and *g* being of relatively large dimensions and entirely free, that is without any subdivision or intermediate subdividing elements. The latter cylinder, which is also composed of material having a high dielectric coefficient and is of a considerably larger internal diameter than the cylinder *c*, ensures the uniformity of distribution of the electric field in the air space *f* due to the high tension winding *h* surrounding the outer cylinder *g*. The uppermost coil or coils of highest potential of the high tension winding *h* are protected by a conducting protecting ring *k* with internal insulation *m*.

The electric stress in the air at the points of highest potential of the high tension winding *h* is such that far below the highest voltage of the transformer streamer discharges occur on the outer cylinder *g*, the uniformity of which is assured by the provision of a conducting discharge ring or shield *i* located on the outer cylinder *g*, which simultaneously protects the uppermost coil or coils of highest potential of the high tension winding against sparking, and by a conducting end ring or shield *p* at the upper end of the

outer insulating cylinder g . These streamer discharges, which as has been ascertained, do not become transformed around an air space into brush or flash discharges, provide for a uniform drop of potential in axial direction of the outer cylinder and therefore permit of very short, direct spacing between the high tension winding and the core. In this case the end ring p which is connected to

10 the yoke of the iron core is of great advantage, as it provides for a uniform distribution of the leakage or creeping currents on the surface of the outer cylinder g .

In order to remove entirely electric stresses between the high tension winding h and the outer cylinder g , the separate coils of the high tension winding may also be connected by so called dielectric soldering to corresponding metal rings r located on the outer cylinder g . These metal rings r ensure a uniform voltage distribution in an axial direction.

By providing one or more intermediate insulating cylinders in the air space f which are provided with conductive sheaths connected to intermediate suitable points in the high tension winding the potential distribution in a radial direction in the air space may be influenced as desired, as will be readily understood.

It has been stated above that the high tension end of the high tension winding h is protected by a discharge ring i surrounding the hollow insulating body g . Such a discharge ring may have various forms. Whereas in the Figures 1 and 2, this ring has a substantially circular cross section near its contacting edge, the discharge ring i^o according to Figures 3 and 4 lies by a sharp edge perpendicularly in contact with the hollow insulating body g . According to Figures 5 and 6, it is provided with a sharp contacting edge i^o turned upwards or downwards, respectively. In the modifications of Figs. 7, 8, 9 and 10, the connection of the discharge ring i^o with the insulating body g is effected by means of an auxiliary connecting ring i^2 placed either inside the main ring i^o (Figure 7), or above it (Figure 8), or below it (Figure 9), the auxiliary ring i^2 being provided with a circular groove i^3 in the form of Figure 10. In the examples of Figures 11 and 12 the discharge ring i^o is provided with an upwardly directed, sharpened discharge edge i^4 at some distance from the insulating body g . Obviously, many other forms may be conceived for the discharge ring.

In all these modifications, the discharge ring is provided as above with the depending protection shell n for uppermost coils of the high tension winding. At its outer end it may be curved downwards for a favorable electric field distribution (Figures 3, 4, 5, 6, 11 and 12), but it may also have the

form of a flat or straight plate (Figures 7 to 10).

What we claim is:—

1. An air insulated high voltage transformer having an iron core, coaxially arranged high and low tension windings thereon, a hollow insulating body for the low tension winding and a larger hollow insulating body for the high tension winding, said hollow insulating bodies being separated by a large, free air space without any subdivision and of such dimensions that streamer discharges only can occur within the electric high tension field, while spark or brush discharges are prevented, for the purpose specified.

2. An air insulated high voltage transformer having an iron core, coaxially arranged high and low tension windings thereon, a hollow insulating body for the low tension winding and a larger hollow insulating body for the high tension winding, said hollow insulating bodies being separated by a large, free air space without any subdivision and of such dimensions that streamer discharges only can occur within the electric high tension field, while spark or brush discharges are prevented, a discharge ring being arranged around the hollow insulating body for the high tension winding, adjacent to the high potential end thereof, for the purpose specified.

3. An air insulated high voltage transformer having an iron core, coaxially arranged high and low tension windings thereon, a hollow insulating body for the low tension winding and a larger hollow insulating body for the high tension winding, said hollow insulating bodies being separated by a large, free air space without any subdivision and of such dimensions that streamer discharges only can occur within the electric high tension field, while spark or brush discharges are prevented, a discharge ring being arranged around the hollow insulating body for the high tension winding, adjacent to the high potential end thereof, and an end ring electrically connected with the iron core being provided around the hollow insulating body for the high tension winding, for the purpose specified.

4. An air insulated high voltage transformer having an iron core, a low tension winding thereon, a hollow insulating body for said winding, a high tension winding coaxially arranged with said low tension winding, a hollow insulating body for said high tension winding, said two hollow insulating bodies being separated by a large, entirely free air space, metal rings being arranged on the hollow insulating body of the high tension winding and electrically connected to the coils thereof, for the purpose specified.

5. An air insulated high voltage transformer having an iron core, a low tension winding thereon, a hollow insulating body for said low tension winding provided with
5 an earthed sheath of conducting material, a high tension winding coaxially arranged with said low tension winding, a hollow insulating body for said high tension winding, said two hollow insulating bodies being
10 separated by a large, entirely free air space, for the purpose specified.

6. An air insulated high voltage transformer having an iron core, a low tension winding thereon, a hollow insulating body
15 surrounding said winding, a high tension winding coaxially arranged with said low

tension winding, a hollow insulating body placed within said high tension winding, said two hollow insulating bodies being separated from each other by a large, entirely ²⁰ free air space, substantially as and for the purpose described.

In witness whereof we have hereunto signed our names this 30th day of March, 1921, in the presence of two subscribing witnesses. ²⁵
